ASSIGNOR TO GEORGE M. TUTTLE, OF NIAGARA FALLS, NEW YORK.

WORK-TABLE FOR A MACHINE FOR DRIVING METALLIC FASTENERS.

1,131,821.

Specification of Letters Patent.

Patented Mar. 9, 1915.

Application filed May 27, 1914. Serial No. 841,344.

To all whom it may concern:

Be it known that we, HERBERT R. BLISS and LEONARD JOHNSTON, citizens of the United States, residing at Detroit, county of Wayne, State of Michigan, have invented a certain new and useful Improvement in a Work-Table for a Machine for Driving Metallic Fasteners, and declare the following to be a full, clear, and exact description of the same, such as will enable others skilled in the art to which it pertains to make and use the same, reference being had to the accompanying drawings, which form a part of this specification.

15 This invention relates to work tables for moving fiber shipping cases which are sealed by wire stitching or metallic fasteners driven into the flaps at the end of the case.

In the drawings, Figure 1, is a side elevation of a wire stitching machine and the work table. Fig. 2, is a plan view of the arm or rack which carries the movable carriage. Fig. 3, is a plan view of the lower truck of the carriage. Fig. 4, is a plan view of the swiveling plate on the upper truck. Fig. 5, is a vertical section showing the pivot upon which the swiveling plate swivels. Fig. 6, shows the ball and spring interlocking which locks the swiveling plate in given positions with respect to the carriage.

20 The head of the wire stitching machine is designated *a* and need not be described as machines of this character are well-known in the art. The upright *b* which supports the stitching head is in the form of a cylindrical column, as shown in Fig. 2. The sleeve portion of the large nut *c* is guided upon this column. The threaded portion of the nut engages with the screw *d* which has a gear *e* 25 on its upper end that is revolved by the worm *f* that in turn is rotated by the crank handle *g*. It is evident that when the crank handle is turned the nut *c* will travel either up or down, depending upon the direction of revolution of the crank handle.

25 The nut *c* has at one side a vertical slot T-shape in cross-section. This is indicated at *h*, Fig. 2. Into this fits the T-bar end *i* of the arm *j*. This arm *j* is shown in a plan view in Fig. 2 and comprises not only the arm proper but also a rack *k* formed of two longitudinal bars and three cross bars, as shown in Fig. 2. One of these longitudinal bars of the rack is provided with a raised 30 rib or track *l* upon which run the wheels *m*

of the lower truck *n* of the movable carriage. A bracket *p* extends from the lower truck under the bar that carries the rib *l* and also serves as a guide for the lower truck as it runs along the rack. From the 35 above, it is evident that the lower truck can travel toward and away from the upright of the machine. Upon the lower truck is carried a track *q* and another track *r*. The track *q* is provided with a rib while the track *r* is preferably smooth. The grooved 40 wheel *s* of the upper truck *t* fits onto the ribbed track *q* and the brackets *u* on each side extend under the lower truck edge to form guides. It is therefore evident that the 45 upper truck *t* can be run transversely of the lower truck.

50 *v* is a screw journaled in the brackets *w* of the lower truck. A pair of nuts *x* run upon this screw. Consequently when the screw *v* is turned the nuts either advance or retreat from each other by reason of the screw *v* being right and left hand. These nuts *x* act as stops which engage with the axles of the wheels *s*. Consequently by adjusting the 55 nuts to the desired position the stopping place of the carriages, when run in either direction, may be determined. These stopping places are determined in reference to the position on the flaps where it is desired 60 to run the row of stitches.

65 A pair of plates *y* is mounted upon the swiveling plate *z* and can be moved transversely of the same by reason of the slotted bracket arms *z* which are held to the plate 70 by the winged screws *1*. The rear end of the plate is provided with a cross plate or angle iron *2* which limits the movement to the rear of the case when the case is placed upon the swiveling plate *z*. The swiveling 75 plate *z* is connected with the upper truck *t* by the pivot *4*. The underside of the swiveling plate is provided with four slight depressions *5* which are located upon a determined circle so that in swiveling 80 these depressions will pass over the spring ball *6* so that a weak temporary lock is effected to notify the operator that one of the four positions in the turn of the swiveling 85 plate has been reached.

90 The operation of the apparatus is as follows: The carrier is drawn out to the end of the rack or arm; one of the plates *y* is loosened and slid slightly to one side to allow the case to be shoved back against the 95 100 105 110

rear plate 2 and the other plate y . Whereupon the plate that has been moved is pushed against the case and held in this position by turning the winged nuts 1. The case is now adjusted upon the carrier, whereupon the arm or rack is moved up to a position (depending upon the height of the case) so that the knife anvil 7 can go in under the flaps when the case is pushed toward the machine. This upward movement is effected by turning the crank which, as already described, moves the entire arm by the screw and nut action. When the proper height has been determined for a case of a given size, it will only be necessary to adjust the case upon the carrier and then move the entire carriage forward. Whereupon the anvil will easily slip in under the flaps. The first row of stitches is taken in the two inner flaps (not shown) and the upper truck is forced over against one of the nuts α so as to accurately determine the position of the first row of stitches in the two inner flaps when this row of stitches has been effected. Then the upper truck is forced over against the opposite nut and this determines the position of the second row of stitches in the inner row of flaps. It is evident that the distance of the stitches apart is determined wholly by the adjustment of the screw v which determines the amount of separation between the nuts α . Inasmuch as a blade-like anvil 7 is used, with large shipping cases it is almost impossible to seal the cases by a row of stitches clear across, for the blade-like anvil has not sufficient rigidity to extend clear across a case twenty or more inches wide. Consequently two operations are necessary. Two rows of stitches are inserted in the flaps from one edge to the center; the box is then turned through 180 degrees, which is possible by reason of the swiveling plate, and when the exact position of parallelism with respect to the anvil of the machine is effected by reason of the ball and depression lock, the carriage is swung back to bring the blade anvil 7 under the inner flaps at the opposite side; thereupon the two rows of stitches are repeated upon this side of the case. This seals the inner flaps.

It is customary in shipping cases to have two sets of flaps: inner and outer flaps; the inner flaps are continuations of two opposite sides while the outer flaps are continuations of the other two sides. Therefore the box is turned around through an arc of 90 degrees to bring the anvil under the two outer flaps. Thereupon the operations enumerated in connection with the inner flaps are repeated with the outer flaps until the box is completely sealed.

What we claim is:

1. The combination with a metallic fastener driving machine, of a blade-like anvil,

a vertically adjustable arm or rack, and a plate or work holder guided upon said rack and movable toward or away from the blade anvil and transversely of said first-mentioned movement and constructed also for 70 swiveling action.

2. The combination with a metallic fastener driving machine, and a blade-anvil therefor, of a rack or arm, and a carriage movable on said rack or arm, the said carriage comprising a lower truck movable toward or away from said blade anvil, an upper truck movable on said first-mentioned truck transversely of the path of movement of said first-mentioned truck, and a swiveling plate carried upon said upper truck. 75

3. The combination with a metallic fastener driving machine and a blade anvil therefor, of an arm or rack, a carriage movable toward or away from said blade anvil 85 on said rack or arm, and comprising a lower truck movable away from or toward said blade anvil, an upper truck mounted on said lower truck and movable transversely of the direction of movement of the lower truck, a swiveling plate mounted on the top of said upper truck, and means for effecting a slight lock in said swiveling plate to determine positions in the arc of swing of said swiveling plate. 90

4. The combination of a machine for driving metallic fasteners and a blade anvil therefor, of a rack or arm adjustable vertically with respect to said machine, and a carriage movable on said rack or arm toward or away from the blade anvil and comprising a lower truck which moves toward or away from the blade anvil, and an upper truck movable on the lower truck in a direction transversely of the movement 100 of the lower truck, and a swiveling plate mounted on the upper truck. 105

5. The combination of a machine for driving metallic fasteners and a blade anvil therefor, of a rack or arm mounted upon 110 said machine, and a carriage movable on said rack or arm toward or away from the blade anvil and comprising a lower truck which moves toward or away from the blade anvil, an upper truck movable on the lower truck in a direction transversely of the movement 115 of the lower truck, a swiveling plate mounted on the upper truck, a plate at the rear and a plate at one side of the upper truck, and an adjustable plate at the 120 other side.

6. The combination with a machine for driving metallic fasteners and a blade anvil therefor, of a rack or arm and a movable carriage comprising a lower truck which moves toward or away from the blade anvil, an adjustable stop on said lower truck, an upper truck movable on the lower truck in a direction transversely of the movement of the lower truck and stopped in either direc- 125 130

tion by said adjustable stop, and a swiveling plate mounted on the upper truck.

7. The combination with a machine for driving metallic fasteners and a blade anvil therefor, of a rack or arm and a movable carriage comprising a lower truck which moves toward or away from the blade anvil, a right and left hand screw journaled in said lower truck, a pair of nuts on the two character threads of the screw, and an upper truck movable on the lower truck in a direction transversely of the movement of the lower truck and stopped in either direction of this movement by said nuts, and a swiveling plate mounted on the upper truck.

8. The combination with a metallic fastener driving machine provided with an upright and a blade anvil supported by said upright, of a rack or arm slideable on said upright, a vertical screw having a screw-threaded engagement with said rack to cause the rack to raise or lower upon the revolution of the screw, means for rotating the screw, and a carriage movable on said rack or arm, said carriage comprising a lower truck movable toward or away from said blade anvil, an upper truck movable on said first-mentioned truck transversely of

the path of movement of said first-mentioned truck, and a swiveling plate movable on said upper truck.

9. The combination with a metallic fastener driving machine and a blade anvil therefor, of a rack or arm and a carriage movable on said rack or arm, the said carriage comprising a lower truck movable toward or away from said blade anvil, an upper truck movable on said first-mentioned truck transversely of the path of movement of said first-mentioned truck, a spring located on the upper truck and a ball tending to be thrust outward by said spring, and a swiveling plate carried upon said upper truck and having recesses arranged to register with the ball in given positions, substantially as described.

In testimony whereof we sign this specification in the presence of two witnesses.
